(57) **CLAIM**

The ornamental design for a boat, as shown and described.

DESCRIPTION

1. Boat

1.1 : Perspective

1.2 : Front

1.3 : Back

1.4 : Top

1.5 : Bottom

1.6 : Left

1.7 : Right

The present design is characterized in that seats are located in a crescent-moon-shaped structure; and a motor assembly supplying power to a boat is provided in a bottom part of a boat which is configured to be parallel to surface of the water, such that it looks like a crescent moon is floating or slipping on the surface of the water when a boat is on the water.
